UNITED STATES PATENT OFFICE.

WILLIAM W. HODGSON, OF CHICAGO, ILLINOIS, ASSIGNOR TO CONTINENTAL CAN COMPANY, INC., OF NEW YORK, N. Y., A CORPORATION OF NEW YORK.

METAL CONTAINER.

Application filed June 17, 1925. Serial No. 37,750.

The invention relates to new and useful improvements in metal containers, and more particularly to a metal container which may be closed so that the contents thereof may be put up under vacuum, and which can be readily opened by the aid of a ripping strip.

An object of the invention is to provide a container of the above character, with a construction of closing end, which, when severed from the body of the container by the aid of the ripping strip, may be again applied to the container as a removable cover held on the body portion by frictional contact therewith.

15 A further object of the invention is to provide a container of the above type wherein the frictional grip between the end and the container body is obtained by the aid of a central depressed portion in the container

20 end and an inwardly projecting curved bead on the body portion, the severing or ripping strip being formed in the container between said bead and the seam at the upper edge thereof securing the end to the container body.

In the drawings which show by way of illustration one embodiment of the invention—

Figure 1 is a sectional view through the 25 container embodying my improvements;

Fig. 2 is a similar view showing the end as severed from the container and again applied as a frictional removable cover for the container;

30 Fig. 3 is an enlarged view showing in detail the structure of the parts contained in Fig. 1 for uniting the end to the container body, so that it may be severed therefrom, and

Fig. 4 is a similar view but showing the 35 end as severed from the container body and again applied as a friction closure.

The invention is directed broadly to a container wherein the end for closing the 40 container is secured thereto by a double seam or some other form of seam, so that the container when closed may be put under vacuum. The container is particularly adapted for putting up tobacco in vacuum.

45 In order that this container may be readily

opened so that access may be had to the contents thereof, the container is scored just below the double seam joining the end to the body of the container, by two parallel lines, so that a strip may be ripped from the body 55 of the container, and thus the end, together with its attaching seam, severed from the remainder of the container body. Just below the lower scoring line there is an inwardly projecting curved bead. The end 60 of the container has a central depressed portion with a vertical wall, the outer face of which is of substantially the same diameter as the inner face of said bead, so that when said end is severed from the container body, 65 the end may be again applied to the container, the central depressed portion extending into the body portion of the container, and the vertical wall referred to making contact with said bead, so as to frictionally hold 70 the end on the container as a removable cover therefor.

Referring more in detail to the drawings, my improved container includes a body portion 1 which is preferably in the form of a 75 cylinder and is closed at its lower end by an end portion 2 which is joined thereto by a double seam 3. This container is provided with an inwardly projecting bead 4, a short distance below the upper end thereof. In 80 the commercial container when completed the bead begins at a point in the cylindrical wall and extends continuously on the arc of a circle inwardly, upwardly and outwardly and terminates in said cylindrical wall. The 85 bead can, therefore, be very easily formed by a spinning tool and made of accurate inner diameter. Between this bead and the upper end of the body portion of the container are two parallel spaced scoring lines 5 and 6 90 forming a ripping strip for severing the portion of the container adjacent the upper edge from the remainder of the container, and on a line just above the bead 4. This ripping strip is provided with the usual 95 tongue 7 which may be engaged by a key so that the strip may be rolled and torn along the scoring lines. The container is closed by means of an end 8 which has a central depressed portion forming a vertical wall 9. 100

The outer flange 10 of this end is rolled into a double seam with the usual flange on the container body, which double seam is indicated at 11 in the drawings.

- 5 The container is especially adapted for putting up tobacco in vacuum. The container is filled with the tobacco, after which the end 8 is secured thereto by the double seam 11 and during the closing of the container, 10 it is put under vacuum. When it is desired to get access to the contents, the rip strip formed by the scoring lines is torn out, thus releasing the closing end from the body portion of the container. The closing end has 15 a very short portion of the body metal still attached thereto. The vertical wall 9 is of smaller diameter than the container, and as a matter of fact, the outer surface of this vertical wall 9 is of substantially the same 20 diameter as the minimum diameter of the inwardly projecting bead 4. This vertical wall 9 is of sufficient length also, so that when the strip is severed from the body of the can releasing the end therefrom, the end may be 25 again placed on the container body and the central portion of the end will pass down into the container body as clearly shown in Figures 2 and 4. When this end is so placed on the container body, the vertical wall 9 30 will frictionally grip the bead 4 and hold the end on as a closure, and thus form a closure for the container which has been opened, which closure can be readily applied and removed from the container body, and 35 will be frictionally held thereon. This frictional grip of the closing end on the container body makes a substantially tight closure, so as to prevent the tobacco in the container from drying out.
- 40 From the above description it will be noted that I have provided a vacuum tobacco container, which, in a measure, is self-contained, and everything goes with the container when sold as an article with the tobacco content therein, which enables the container to be quickly opened, and the opening of the container provides a reclosure for the container. That is to say, the ripping strip severs the body portion, so that the end 45 with the depressed portion can engage the inwardly projecting bead and thus form of the end and the severed portion attached thereto, a closure. When the end, as a closure, is applied to the container body, and 50 the vertical wall engages said bead, that portion of the container which is still attached to the removed double seam, now a part of the closure, will engage the upper edge of the re-formed body, and limit the inward movement of the closure. In other words, the closure may be forced into the bead, and constructed so that some little 55 force is required to cause the closure to be applied to the container, and at the same 60

time, the distance which said end is forced into the closure is limited. The scoring line 6 is positioned just above the bead 4, so that there is substantially no raw edge of material liable to cut the hand in reaching into the container. That is to say, the upper curved portion of the bead forms, in a measure, the mouth portion of the container body after the end is severed therefrom by the aid of the rip strip.

It is obvious that minor changes in the details of construction and the arrangement of the parts may be made without departing from the spirit of the invention as set forth in the appended claims.

Having thus described the invention, what I claim as new and desire to secure by Letters Patent, is—

1. A commercial metal container when completed comprising a cylindrical body portion and a closing end secured thereto by a double seam, said body portion having an inwardly projecting semi-circular bead in the wall thereof, said bead being spaced from the upper end of the body portion and beginning at a point in the cylindrical wall and extending continuously on the arc of a circle inwardly, upwardly and outwardly and terminating in said cylindrical wall, said body having parallel score lines between the bead and the upper end thereof forming a ripping strip having a projecting tongue to aid in tearing the metal along the score lines, one of said score lines being disposed just below the double seam and the other just above the upper edge of said bead, said closing end having a depressed portion providing an inset vertical wall, the diameter of which is slightly greater than the inner diameter of said bead, said inset vertical wall lying below the upper score line so as to frictionally engage said bead for re-closure after the ripping strip has been removed.

2. A metal container comprising a cylindrical body portion having an inwardly projecting semi-circular bead in the wall thereof, said bead being spaced from the upper end of the body portion, said body portion having parallel scoring lines between the bead and the upper end thereof forming a ripping strip, said ripping strip having a projecting tongue to aid in tearing the metal along the scoring lines, a closing end having a central depression and an outwardly projecting flange adapted to be formed with the flange of the body into a double seam, the upper scoring line being located just below said double seam, and the lower scoring line being located just above the upper edge of said bead, said depressed portion of the end having an inset vertical wall starting at and extending downwardly from a line lying in substantially a horizontal plane containing

the upper score line, the diameter of said inset portion being slightly greater than the inner diameter of said bead whereby after said end has been severed from the body portion of the container by the aid of the ripping strip, said end can be placed on the container body with the vertical wall fric-

tionally engaging said bead and the ruptured edges in the body in engagement with each other and serving as a stop for limiting the inward movement of the vertical wall along said bead. 10

In testimony whereof, I affix my signature.
WILLIAM W. HODGSON.
